UNITED STATES PATENT OFFICE.

REINHARD KLINGELHÖFFER, OF WERDEN-RUHR, GERMANY, ASSIGNOR TO FRIED.
KRUPP AKTIENGESELLSCHAFT, OF ESSEN-ON-THE-RUHR, GERMANY.

TURBINE LOCOMOTIVE.

Application filed January 22, 1924. Serial No. 687,853.

To all whom it may concern:

Be it known that I, REINHARD KLINGELHÖFFER, residing at Werden-Ruhr, Germany, a citizen of the German Empire, have invented a certain new and useful Improvement in Turbine Locomotives, of which the following is a specification.

With locomotives consisting of piston steam engines the main point in braking the train is only the destroying of the kinetic energy which corresponds to the linearly moved mass of the train, since the part of the kinetic energy involved by the rotary energy of the rotating elements (wheels and axles) is comparatively small. With turbine locomotives, however, the rotary energy of the rotating elements to be destroyed is very large on account of the high number of revolutions of the turbine rotors and of some parts of the gearing transmitting the work of the turbines to the driving axles, so that the said rotary energy will act disadvantageously in the braking of the train by increasing the braking distance.

Now, the invention has for its object to provide a turbine locomotive with which the disadvantageous influence on the braking distance of the rotary energy of the rotating elements of the turbines and the parts of the gearing which are in direct connection with the said elements, is obviated.

An embodiment of the subject-matter of the invention is illustrated in the accompanying drawing, in which:

Fig. 1 is a partial side elevation of a turbine locomotive,

Fig. 2 is a section of a detail on an enlarged scale,

Fig. 3 is an elevation of Fig. 2, and

Figs. 4 to 7 are views of another detail in different positions.

The working steam is supplied to the ahead turbine A of the locomotive from the main distributing valve B through the valves b¹ and b² and the conduits a¹ and a², while the valve b³ is in communication with the back turbine R through the conduit a³. The space b⁴ (Fig. 2) which is being closed by the valve b³ and which is directly connected with the back turbine by the conduit a³, is in communication with a space C which is adapted to be closed by an auxiliary valve E. The space C is connected by a conduit D with the portion of the steam dome of the locomotive which is not influenced by

the governor. The valve E is constantly held in contact with a bell-crank lever F by the steam pressure, this lever being mounted for rotation on a pin f¹ and connected by a rod G with a lever H provided in the driver's cab. The lever H is mounted for free rotation on the shaft J which serves to throw the train brake in and out. It carries an auxiliary lever K, which is under the action of a spring k¹ and forms a locking bolt k² which, in the position according to Figs. 4-6, engages a notch i² of a disk i¹ which is rigidly fastened on the shaft J. The actual brake lever L is rigidly connected with the shaft J.

The braking operation is commenced by swinging the brake lever L in the direction of the arrow x (Fig. 5). The shaft J takes part in this rotation of the lever L and carries the lever H along with it through the intermediary of the coupling i² k². The rod G is thus shifted towards the turbine causing a clockwise rotation of the bell crank lever F. The lever F thereby releases the valve E so that working steam will flow through the conduit a³ into the back turbine R. The back turbine will therefore tend to rotate in the sense of the astern drive of the train and will thus exert a braking action on the train. The valve E is of such dimensions that, when the train brake is set for rapid action which corresponds to the largest opening of the valve E, the effort produced by the back turbine during the braking operation will be approximately equal to the rotary energy of the rotating parts of the driving engines. When the train has been caused to stop and the train brake is not allowed to be immediately released (such as for instance when stopping on sloping ground), the locking bolt k² is disengaged from the notch i² by a pull at the lever K and the lever H returned into its initial position (Figs. 5 and 7). The valve E is thereby closed again through the shifting of the rigging G F and the back steam is cut off. In order to release the train brake, the lever L is then likewise returned into its initial position. As soon as the lever L has reached its initial position (Figs. 5 and 7), the locking bolt k² will snap again into the notch i² under the action of the spring k¹ and re-couple the levers H and L.

In case the locomotive is mostly used for

running forwards, while it should only be driven at moderate speed when running backwards, it will be sufficient to provide only the back turbine with the above-described device. If, however, the locomotive should equally well be adapted for both directions of running, such as is for instance the case with tank engines, the ahead turbine must likewise be provided with a corresponding device.

As a matter of fact, the braking of the rotary energy of the rotating parts of the driving engine may also be effected by providing a mechanical brake adapted to be thrown in by the rigging H, G, F.

Claims:

1. In a turbine locomotive a train brake and a mechanism for throwing the train brake in and out, means for directly braking the rotary energy of the rotating parts of the turbine upon the train brake being thrown in, said means being arranged so as to be in positive engagement with the said mechanism during its action of throwing in the train brake.

2. In a turbine locomotive comprising an ahead turbine and a back turbine, a train brake and a mechanism for throwing the train brake in and out, this mechanism being in a positive connection with an auxiliary valve of the back turbine so as to cause this auxiliary valve to be opened and working steam to be supplied through this valve to the back turbine when the train brake is thrown in.

3. In a turbine locomotive comprising an ahead turbine and a back turbine, a train brake and a mechanism for throwing the train brake in and out, an auxiliary valve on the back turbine, said valve being connected with the mechanism for throwing the train brake in and out and adapted to be opened by the said mechanism when the train brake is thrown in for allowing working steam to flow into the back turbine for braking purposes during the running for-

wards of the locomotive, and an auxiliary valve on the ahead turbine likewise connected with the mechanism for throwing the train brake in and out and adapted to be opened by the said mechanism when the train brake is thrown in for allowing working steam to flow into the ahead turbine for braking purposes during the running backwards of the locomotive.

4. In a turbine locomotive comprising an ahead turbine and a back turbine, a train brake and a mechanism for throwing the train brake in and out, both turbines being provided each with an auxiliary valve, connecting means between these auxiliary valves and the mechanism for throwing the train brake in and out, the auxiliary valve of the back turbine being adapted to be opened so as to allow working steam to be supplied to the back turbine when the train brake is thrown in during the running forwards of the locomotive, while the auxiliary valve of the ahead turbine is adapted to be opened so as to allow working steam to be supplied to the ahead turbine when the train brake is thrown in during the running backwards of the locomotive, each of the auxiliary valves being of such dimensions as to cause the effort produced by the braking turbine during the act of braking to be approximately equal to the rotary energy of the rotating parts of the driving engines.

5. In a turbine locomotive comprising an ahead turbine and a back turbine, a train brake and a mechanism for throwing the train brake in and out, both turbines being provided each with an auxiliary valve, and these auxiliary valves being connected by an easily releasable coupling with the mechanism for throwing the train brake in and out.

The foregoing specification signed at Essen, Germany, this sixteenth day of November, 1923.

REINHARD KLINGELHÖFFER.
